UNITED STATES PATENT OFFICE.

CARBON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTH DAKOTA.

PROCESS FOR TREATING HYDROCARBONS.

Application filed May 24, 1924. Serial No. 715,632.

To all whom it may concern:

Be it known that I, CARBON P. DUBBS, a citizen of the United States, residing in the village of Wilmette, county of Cook, 5 and State of Illinois, have invented certain new and useful Improvements in Processes for Treating Hydrocarbons, of which the following is a specification.

This invention relates to improvements in 10 a process for converting hydrocarbon oils whereby maximum yields of low boiling point oils are obtained without the production of a substantial quality of liquid residuum in the conversion chamber.

15 I have discovered that when oil is subjected to cracking conditions of heat and pressure, if it is mixed with a definite quantity of reflux condensate, that the volatile content of the oil on passing to an expansion 20 or conversion chamber will undergo complete evaporation, separating into vapors and a solid residue, without requiring the application of such excessive heat as to cause substantial deposition of carbon in 25 the cracking tubes.

I have found in practice that in the use 30 of a reflux conversion process such as broadly described in my Patent No. 1,392,629, that by increasing the quantity of reflux condensate admitted to the cracking coil with the raw charging stock, considerably above the quantity now generally cycled in the usual residuum runs, that the 35 mixed oil passing through the cracking coil and entering the large conversion chamber will, under its own heat, separate into vapors and a substantially solid residue without so severely heating the oil as to deposit such quantities of carbon in the cracking tubes 40 to coke the same, or cause destruction thereof. I am not fully aware as to why this reaction occurs during the treatment, but I do know that when temperatures and pressures are properly maintained, and a 45 sufficient quantity of reflux condensate is used in proportion to the raw oil, that substantially complete evaporation of the volatile content of the oil occurs without the formation of excessive carbon deposits in 50 the heating zone, leaving in the expansion chamber only a residue of coke-like bodies largely free of liquid oil.

In the drawings, I have shown a side elevation of an apparatus capable of supporting 55 this process.

Referring now more particularly to the drawing wherein like reference characters indicate corresponding parts, the numeral 1 designates a furnace containing the heating coils 2 that are preferably of 4" diameter and of such a length as to represent approximately 1500 square feet of heating surface. This heating coil is fed by a charging line 3 introducing charging stock continuously thereto, consisting of a mixture of reflux condensate and raw oil. The charging stock passes through the cracking tubes 2 in a continuously advancing stream, reaching a liquid transfer temperature of 850° F., more or less, and when at substantially this temperature, is delivered to the expansion or conversion chamber 7, which is a heavily insulated receptacle located outside of the zone of heat and approximately 10 feet in diameter and 15 feet 60 in height. The transfer of oil occurs by means of the heavily insulated transfer line 5 in which there is positioned a valve 6 for a purpose to later appear. The chamber 7 is formed with top and bottom closures 65 and 9 respectively. These closures are removable to permit residue to be removed from the chamber. In the chamber 7 the volatile content of the oil admitted thereto substantially completely vaporizes. That is to say, the volatile content of the oil vaporizes leaving as a residue solid coke-like particles that accumulate in the chamber 7. This residue may contain some heavy 70 liquid oil but it is an aim of the invention to, as far as possible, eliminate all such liquid oil and to keep the residue substantially free thereof. The vapors representing the bulk of the oil, pass out through the line 10, controlled by the independently operable valve 11 and enter the lower end of the dephlegmator 12 for passage 75 there-through.

This dephlegmator can be of any well known construction. As shown, however, 80 it is provided with a series of baffles or pans 13 to retard the passage of vapors therethrough, the uncondensed vapors from the dephlegmator passing through the line 16 controlled by the valve 17 into a final condenser 18, seated in a condenser box 19, the 85 pressure distillate accumulating in the tank 20, having a gas discharge line controlled by a valve 21 by means of which a superatmospheric pressure may be maintained 90

throughout the system. The distillate is discharged through either the line 23, or the line 24, continuously or intermittently. The temperature of the dephlegmator 12 is maintained sufficiently high so as to condense vapors, that have not been sufficiently cracked, by the cooling effect of pressure distillate introduced thereto by the pump 26 forcing the distillate through the pipe 26 forcing the distillate through the pipe 26.

5 27 having the manually controlled valve 28 therein, or in lieu of using pressure distillate as a cooling medium the charging stock admitted to the pump 4 may in part be passed through a line 13' by a proper 70 control of the valve 14' and 15' and at the same time a portion of this charging stock is also admitted to the cracking coil through 75 the line 3. In other words, the temperature of the dephlegmator may be controlled 80 by the introduction of pressure distillate or charging stock thereto, or by a mixture of both. Substantial quantities of the vapors are condensed in the dephlegmator and this condensate drops down into the pressure leg 85 25 13' from which it is discharged to mix with the raw oil at the point X, the mixture of the two substances passing directly to the coil 2.

The expansion chamber 7 is shown as being 90 provided with residual drawoff lines 29 controlled by the valves 30. These residual lines, however, remain closed during the normal operation of the process as no liquid residuum is drawn from this chamber after 95 35 the process is in operation. This is because the residue remaining in the chamber 7 is substantially solid in nature as distinguished from the liquid residuum that is usually continuously discharged from an expansion 100 40 chamber in conversion processes of this general character. Of course, a little liquid oil may collect from time to time in the chamber 7 in which event the oil can be withdrawn as necessary.

45 In describing briefly the process forming the subject matter of this invention, charging stock mixed with reflux condensate passes through the tube 2 where it is heated from 800° to 900° F. under a superatmospheric 105 50 pressure of say 120 pounds, and is admitted to the chamber 7. Either in the coil, or in the chamber, or in both, the oil separates into vapors, and a substantially solid coke-like residue, which accumulates in the chamber 55 110 7. The vapors which represent substantially the entire volatile content of the oil treated, discharge through the line 10 controlled by the valve 11 into a dephlegmator 12 which may be maintained at its discharge 115 60 at a temperature of say 525° F., more or less, or such temperature as will cause the production of a desired pressure distillate and a sufficient quantity of reflux condensate to enable the process to be carried out.

65 This temperature results in a substantial

condensation of the vapors admitted to the dephlegmator, the reflux condensate dropping into the leg 13' and being returned by means of the line 14 with or without a pressure pump, to the cracking coil with a 70 relatively small quantity of raw charging stock passing through the line 3. The reflux condensate may approximate a temperature of say 700° F., more or less, while the vapors discharging from the dephlegmator may be of a temperature of say 525° 75 F., but of course, these temperatures will materially vary depending upon the character of the oil being treated as well as the products desired, and are only given as illustrations for some oils I have used. When an apparatus is being placed in operation and before operating conditions of temperature and pressure have been satisfactorily reached, and before the chamber has been 80 sufficiently heated, the oil passed through the cracking tube and into the chamber 7 is withdrawn therefrom through the lines 29 and 30.

In carrying out my process, it may be desirable at times to maintain different pressures on various parts of the apparatus. For instance, a pressure of 120 pounds per square inch could be maintained on the coil 2 by controlling the valve 6, and a reduced 90 pressure of 75 pounds maintained on the chamber 7, dephlegmator 12 and condenser 13 by controlling the valve 21. It is also apparent that by controlling the valve 11, the chamber 7 could be maintained under a 100 pressure above that maintained in the remaining portions of the apparatus. To increase the running period of the apparatus, I may at times split the stream of heated oil passing from the coil and simultaneously 105 admit different portions thereof to two or more expansion chambers 7 having independent dephlegmators and condensers.

To give an illustrative run of this non-residuum process, I will first refer to the 110 usual residuum run carried out in this apparatus in order to compare the differences in operation which must be followed to cause substantially complete vaporization of the oil in the expansion chamber without depositing excessive quantities of coke in the tubes. In the usual residuum run, that is, a run where residuum is continuously withdrawn from the chamber 7, I treated a topped Smackover crude of 17.7 degrees 115 Baumé gravity, and during a period of thirteen hours in the apparatus just described, 17,240 gallons of this oil was treated. I obtained 9,520 gallons of pressure distillate of 50° Baumé gravity. 32% of the raw 120 charge treated represented liquid residuum and 13% gas and coke. The distillate thus obtained, represented 55% of the raw oil charge. During this run, I heated the oil to a liquid transfer temperature of approxi- 125 130

208-103

1,551,090

3

mately 890° F., while I maintained the temperature of the vapors leaving the dephlegmator at approximately 565° F., at the upper discharge end thereof. A pressure of 5 120 pounds per square inch was maintained during this run throughout the system.

As an illustrative run of the process herein described, I used the same oil, that is, a topped crude from the Smackover field of 10 17.7 degrees Baumé gravity in the apparatus herein set forth. In a period of 13 hours, 14,920 gallons of raw charging stock was passed through the cracking tubes 2. With this oil, a large quantity of reflux 15 condensate was also passed through the coil. I have been unable to ascertain the exact proportion of condensate to the charging stock that I admitted, but I do know that by maintaining the temperature of the reflux 20 from the dephlegmator 12 at approximately 725° F., and in the desired quantity, the process described can be successfully carried out. The charging stock during 25 passage through the cracking coil 2 was heated until its transfer temperature approximated 895° F. The pressure maintained throughout the system during the run was 120 pounds per square inch. In the 30 chamber 7 the heated oil separated entirely under its own heat into vapors representing approximately 80% of the charge, and a residue consisting of substantially solid coke-like bodies largely free of residual oil, and of a non-fluid consistency. This residue 35 approximated 18% of the total oil charge, 2% of the oil treated representing incondensable gas. The vapors from the chamber 7 were passed through the line 10 and when discharged into the dephlegmator 12 40 were of a temperature of approximately 820° F. The top exit temperature of the dephlegmator by introduction of pressure distillate through the line 27' or charging stock through the line 13' was lowered to a 45 temperature of 500° F. immediately after the flow of liquid residue from the expansion chamber was discontinued, or in other words, at the time the plant was being transferred from a residuum run to a non- 50 residuum run. At this time it will be understood that the various parts of the apparatus had been sufficiently heated, and the treated oil had attained a temperature sufficient to carry out the process. This low 55 temperature in the dephlegmator resulted in a condensation of a most substantial quantity of the vapors admitted thereto. The condensate with the infed oil introduced to the top of the dephlegmator collected in the leg 13^d, and as before stated was of a temperature approximately 725° F. The uncondensed vapors were continuously discharged from the dephlegmator and passed 60 to the condenser 18, collecting as pressure 65 distillate in the receiver 20. Approximately

12,200 gallons of pressure distillate were made during this run from the 14,920 gallons of charging stock, the distillate representing approximately 80% of the charging stock.

70

It will be understood that this sudden drop in the temperature of the dephlegmator results in an immediate production of increased ratio of reflux condensate to the charging oil passing to the heating coil. 75 This additional quantity of condensate which is a low boiling point oil results in the production of increased quantities of vapors in the expansion chamber after passage through the heating coil. These vapors on passing to the dephlegmator will again gradually raise the temperature of the dephlegmator to substantially or near its original point without decreasing the quantity of cooling oil fed to the top of the dephlegmator. At the same time the same increased 80 ratio of reflux condensate to the charging oil is maintained in the cycle.

85

I am not familiar with the exact reaction that occurs in carrying out this process, but I believe that the complete distillation can perhaps be attributed to the relative large quantity of reflux that is used with the charging stock. This quantity of reflux is substantially greater than the quantity used 90 in the usual residuum runs. I fully appreciate the result however, that follows the operation of the process as described, and I have successfully treated the oil referred to by this process producing only vapors and a 95 substantially solid residue that accumulates 100 in the chamber 7.

100

By comparing the foregoing run with the usual residuum run, it will be seen that in the residuum run I fed substantially more charging stock than I did of the non-residuum run, but mixed with this charging stock a substantially less quantity of reflux condensate. During these two runs, I maintained substantially the same furnace temperature, and the transfer temperature of the oil was approximately the same. In operating the non-residuum run however, and when switching the plant into this operation, I initially drop the temperature of the dephlegmator to approximately 500° F., which results in the formation of an increased quantity of reflux condensate to be continuously mixed with the charging stock 115 of a decreased quantity. Naturally, with the lower temperature in the dephlegmator, I condense greater quantities of the vapors, and once having attained an operation where a greater proportion of condensate is admitted to the coil with the charging stock 120 than used in the conventional residuum run, the increased quantities of vapors entering the dephlegmator due to the larger quantity of reflux condensate returned to the coil by the drop in the temperature of the dephleg- 125

mator gradually raises the temperature of the dephlegmator until the vapors leave at a temperature of up to 565° F. or at any point desired depending upon the character 5 of distillate the user of the process is seeking to obtain. This rise in temperature, however, does not destroy the higher ratio of reflux to the charging stock, as I have found that when this ratio is once obtained it will 10 continue during the normal operations of the plant even though the discharge temperature of the vapors of the dephlegmator will rise. However, should the quantity of reflux fall below that necessary to accomplish 15 the results set forth in this application, then I may intermittently drop the temperature of the dephlegmator until the desired quantity is produced.

In the operation just described, I found 20 that when the transfer temperature of the oil approximated 895°, that if the dephlegmator temperature was dropped to 500° F., the reflux would collect in the leg in sufficient quantities to support this process, and 25 would approximate a temperature of 725° F. The temperature of the vapors issuing from the dephlegmator will gradually rise as increased quantity of reflux condensate are admitted to the coil without decreasing 30 the quantity of cooling oil admitted to the dephlegmator. This rise in temperature, however, does not destroy the ratio of condensate to the charging stock. However, in bringing the process on stream, and as soon 35 after the valves 30 in the drawoff line 29 are closed, and just previous to the dropping of the temperature in the dephlegmator, some liquid oil may accumulate in the chamber 7. Such oil would accumulate because 40 the expansion chamber is not sufficiently heated, or because the oil is not at the desired transfer temperature. This liquid oil however, is gradually evaporated during the 45 non-residuum run by reason of heat units imparted thereto by the large quantity of incoming oil at a temperature higher than the temperature of the liquid oil accumulat- ing in the chamber 7.

In the foregoing specification, I have 50 clearly pointed out and actually described certain commercial operations which I have performed with a given oil. Various other oils have also been treated by this process where slightly different temperatures were 55 used, but it is thought that the description of the treatment of one well known oil will suffice for the present purpose. In treating any oil, it is only necessary that the reflux condensate cycled with the charging stock 60 be of a certain desirable temperature, and in certain definite quantities in excess of the quantities now generally used in the residuum run.

Having now described my invention, what 65 I claim is:

1. A process for the conversion of hydrocarbon oil into lower boiling point hydrocarbon products, consisting in passing a stream of reflux condensate and charging oil through a heating tube where the mixture is heated to a cracking temperature without raising the temperature of the oil so high as to cause substantial deposition of carbon in the tube, passing the heated mixture from the tube to an enlarged reaction chamber where the oil mixture after passing through the tube separates without any substantial rise in its temperature into vapors and a non-flowing carbon residue largely free from residual oil and maintaining a superatmospheric pressure on the oil in said conduit and in said enlarged chamber, the ratio of the reflux condensate to the charging stock and the amount of heat supplied to the tubes being maintained sufficient to cause the separation of the oil mixture into said non-flowing carbon residue and vapors in the reaction chamber. 70 75 80 85

2. A process for the conversion of hydrocarbon oil into lower boiling point hydrocarbon products, consisting in mixing a distillate with a relatively heavier charging stock having a boiling point range substantially differing from the boiling point range of the distillate, in passing the mixed hydrocarbon substances through a heating tube where a stream of such oil is heated to a cracking temperature without raising the temperature of the oil so high as to cause substantial deposition of carbon in the tube, 90 95 100 in passing the heated mixture from the tube to an enlarged reaction chamber where the oil mixture separates without any substantial rise in its transfer temperature into vapors and a non-flowing carbon residue largely free from residual oil, and maintaining a superatmospheric pressure on the oil in said tube and in said enlarged chamber, the ratio of the distillate to the charging stock having the substantially different 105 110 boiling point range and the amount of heat supplied to the oil stream passing through the tube being maintained sufficient to cause the separation of the oil mixture into said non-flowing carbon residue and vapors in the reaction chamber. 115

3. A process for the conversion of hydrocarbon oil into lower boiling point hydrocarbon products, consisting in mixing relatively light and heavier hydrocarbon oils, 120 one having a boiling point range substantially differing from the other, in passing the composite stream of oil through a heating tube where said stream is heated to a cracking temperature without raising the temperature of the oil so high as to cause a substantial deposition of carbon in the tube, passing the heated hydrocarbon material mixture from the tube to an enlarged reaction chamber where the hydrocarbon 125 130

5

- material separates without any substantial rise in its transfer temperature into vapors and a non-flowing carbon residue largely free from residual oil, in maintaining a 5 superatmospheric pressure on the oil in said tube and in said enlarged chamber, and in controlling the ratio of the oil having one boiling point range to the oil having the different boiling point range forming the 10 composite charging stock and the amount of heat supplied to the tube to cause the separation of the oil mixture into said non-flowing carbon residue and vapors in the expansion chamber.
- 15 4. A process for the conversion of hydrocarbon oil into lower boiling point hydrocarbon products, consisting in mixing a distillate that has once been subjected to a cracking treatment with a charging oil that 20 has not been subjected to such a treatment and which charging stock has an end point substantially higher than the end point of the distillate, in passing the mixed hydrocarbons through a heating tube where the 25 oil mixture is heated to a cracking temperature without raising the temperature of the oil so high as to cause substantial deposition of carbon in the tube, in passing the heated mixture from the tube to an enlarged reaction chamber where the hydrocarbon mixture separates without any substantial rise in its temperature into vapors and a non-flowing carbon residue largely 30 free from residual oil, and maintaining a superatmospheric pressure on the oil in said tube and in said enlarged chamber, the ratio of the distillate to the charging oil and the amount of heat applied to the tubes being maintained sufficient to cause the separation 35 of the oil mixture into said substantially non-flowing residue and vapors in the reaction chamber.
- 40 5. An oil conversion process, consisting in passing a stream of reflux condensate and charging oil through a heating tube to be heated to a cracking temperature without raising the temperature of the oil so high as to cause objectionable carbon deposition in said tube, in transferring the heated hydrocarbon material after passing through the heating tube to an enlarged reaction chamber where the oil separates without any substantial rise in its transfer temperature into vapors and a non-flowing residue consisting of carbon substantially free from liquid residual oil, in subjecting the vapors to reflux condensation, in maintaining a superatmospheric pressure on the oil in the heating tube and in the reaction chamber, the ratio of the reflux condensate to the charging oil being maintained such that under said conditions of heating in the tube the oil mixture separates in said reaction chamber into the non-flowing residue and vapors.
- 45 6. An oil conversion process, consisting in passing a stream of reflux condensate and charging oil through a heating tube to be heated to a cracking temperature without raising the temperature of the oil so high as to cause objectionable carbon deposition in said tube, in transferring the heated hydrocarbon material after passing through the heating tube to an enlarged reaction chamber where the oil separates without any substantial rise in its transfer temperature into vapors and a non-flowing residue consisting of carbon substantially free from liquid residual oil, in subjecting the vapors to reflux condensation, in maintaining a superatmospheric pressure on the oil in the heating tube, the reaction chamber and the reflux condenser, the ratio of the reflux condensate to the charging oil being maintained such that under said conditions of heating in the tube the oil mixture separates in said reaction chamber into the non-flowing residue and vapors.
- 50 7. An oil conversion process consisting in passing a composite stream of relatively light and heavier hydrocarbon oils through a heating tube where the oil is subjected to a cracking temperature without raising the temperature of the oil so high as to cause substantial deposition of carbon in the tube, in transferring the heated hydrocarbon material to an enlarged zone, in effecting a separation of the heated hydrocarbon material in said enlarged zone into vapors and a substantially non-flowing carbon residue by controlling the composition of the charging oil and the amount of heat applied to the heating tube, and in maintaining a superatmospheric pressure on the oil undergoing treatment.
- 55 8. A process for the conversion of hydrocarbon oil into lower boiling point hydrocarbon products, consisting in mixing relatively light and heavier hydrocarbon oils, having different boiling point ranges, in passing the composite stream of oil through a heating tube where said stream is heated to a cracking temperature without raising the temperature of the oil so high as to cause a substantial deposition of carbon in the tube, passing the heated oil mixture from the tube to an enlarged reaction chamber where the oil separates into vapors and a substantially non-fluid residue, in controlling the ratio of one of the oils to the other forming the composite charging stock and the amount of heat supplied to the tube to cause the separation of the oil mixture into a substantially non-flowing carbon residue and vapors in the expansion chamber, and in maintaining a superatmospheric pressure on the oil undergoing conversion.
